UNITED STATES PATENT OFFICE.

WILLIAM W. TUCK, OF NEW YORK, N. Y., ASSIGNOR TO VELOX MANUFACTURING COMPANY, OF NEW YORK, N. Y., A CORPORATION OF NEW YORK.

ADDRESSING-MACHINE.

1,094,824.

Specification of Letters Patent. Patented Apr. 28, 1914.

Application filed October 29, 1912. Serial No. 728,426.

To all whom it may concern:

Be it known that I, WILLIAM W. TUCK, a citizen of the United States, residing at Richmond Hill, in the county of Queens, 5 city and State of New York, have invented certain new and useful Improvements in Addressing-Machines, of which the following is a specification.

This invention relates to machines for 10 printing addresses upon envelops, wrappers, cards and the like, using therefor suitably prepared stencils. The machine is specially adapted for operation with stencils formed from porous tissue or coated paper pasted or 15 otherwise secured to a rectangular frame of card-board or similar material.

The object of the invention is to effect 20 numerous improvements in the construction and arrangement of the parts of machines of this type, whereby more rapid, uniform and reliable operation of the machine may be secured, and whereby adjustments may be readily effected in order that the addresses 25 may be printed in the desired positions upon the envelops or wrappers.

In its general construction the machine embodies an upright magazine for the stencil-cards from which the cards are removed edgewise, from the bottom of the magazine, 30 successively. The cards are moved laterally from the magazine in suitable guides and then downwardly to the printing position, in which position they are held until grasped and forwarded by the printing-members. 35 The printing-members consist of two coacting rolls of segmental form, one a platen-roll and the other an inking-roll. The faces of these rolls grasp the sheet to be printed and the stencil between them, applying the ink 40 to the stencil, effecting the printing and forwarding the stencil and sheet from the printing position.

The invention involves the provision of an improved construction for the magazine and 45 improved form of feeder or picker whereby the stencil-cards are moved successively from the magazine, improved retaining means for holding the stencil-cards after they are moved from the magazine in such manner 50 that accurate registration, alinement and adjustment may be secured, improved adjustable sheet-feeding devices whereby the position of the printing upon the sheet may be regulated as desired, and improved devices

for forwarding and packing the sheets and 55 stencils after the printing has been effected.

The preferred embodiment of the invention is illustrated in the accompanying drawings in which:

Figure 1 is a side elevation of the machine, 60 the magazine being removed and the supports therefor being broken away; Fig. 2 is a horizontal sectional view above the surface of the table, the top of the table itself being removed so as to disclose the underlying 65 mechanism; Fig. 3 is a vertical sectional view through the feeding and printing mechanism; Figs. 4, 5 and 6 are detail views of the mechanism for packing the stencil-cards; Fig. 7 is a detail view showing the clutch 70 mechanism; Fig. 8 is a vertical sectional view of certain of the operating parts including the actuating means for the picker or feeder; Figs. 9 and 10 are views illustrating the exit for the stencil-cards from the 75 magazine; and, Figs. 11 and 12 are sectional views illustrating the cam adjustment for the sheet-feeding mechanism.

Referring to the drawings, the parts of the machine are mounted upon a table having a top 1 and legs 2. On the top 1 are secured certain uprights 3 which support a stack of stencil-cards, the stack being vertical, with the several cards thereof horizontally disposed, one above another. The stencil-cards are preferably made from stencil-paper of any well known form, pasted upon frames of card-board or similar material. 80 The two uprights 3, at the front of the magazine, are of angular cross-section as 85 shown in Figs. 3 and 9, and the forward walls thereof are cut away, as indicated at 4, in Figs. 9 and 10. A guide 5 is secured to each of these forward uprights 3 and serves to position a vertically movable stop 6, there 90 being one stop 6 secured to each of the uprights 3 at the forward side of the magazine. 95 Each stop 6 has a screw passing through an offset thereon and a similar offset secured to the upright 3, around which screw is coiled 100 a spring 7. The spring 7 tends to force the stop 6 downwardly so as to carry an abutment or plate 8 secured to the stop downwardly into engagement with the upper face of the block 9 at the bottom of the magazine. 105 The lower edge of the piece 8 is inclined as shown in Fig. 10 and curved or beveled on the side toward the interior of the magazine.

The two independently movable spring-actuated stops 8 at the exit from the magazine serve to prevent more than one stencil-card from being moved out of the magazine at 5 one time. As a card is moved laterally from the bottom of the pile in the magazine its edge engages the rounded edge of each stop 8 and lifts the stop against the tension of its spring 7 sufficient to allow the card to 10 be moved under the stop, but if the next higher card is being moved with the lower one its edge will be caught by the two stops 8 and these stops will offer sufficient resistance to the movement of the card to preclude it 15 from raising the stops and moving under them out of the magazine.

The cards as they move from the magazine are guided by two guides 10, preferably formed from sheet-metal strips bent to a 20 U-shaped cross-section. These guides 10 at their upper ends are secured to the magazine, one on either side thereof and extend forwardly from the forward face of the magazine. The guides are then curved 25 downwardly so that through a portion of their length they are approximately vertical and below this point the guides may be of whatever shape desired in order to conduct the stencil-cards to the packer or other receptacle after the printing has been effected. To each guide 10 is secured a plate 11 (Fig. 9), on which plate two levers are pivotally mounted. One of these levers 12 constitutes 30 a stop or positioning device. The other 13 is a brake or holder for holding a stencil-card until it is engaged by the printing rolls. Both levers 12 and 13 are pressed by 35 springs 14 to turn them on their pivots into engagement with a stencil-card or the opposite wall of the guide 10. The plate 11 is secured to the guide 10 by screws 15 passing 40 through an arc-shaped slot in the plate 11 so that the plate with the levers 12 and 13 thereon may be adjusted lengthwise of the 45 guide 10 to bring it to the desired position and locked in that position.

The picker or feeder for the stencil-cards comprises arms 16 pivotally mounted upon a shaft hereinafter referred to. The free 50 ends of these arms are connected by a rod which forms a pivotal support for two arms 17, each of which has a projection 18 upon its upper edge and adjacent to its free end. The arms 17 are in the form of bell-crank 55 arms as shown in Fig. 3, and the downwardly extending arm of each bell-crank has a pin thereon which is connected by a spring 19 to a pin on the adjacent arm 16 so that the spring serves to turn the arm 17 on its pivot 60 in a direction to elevate its free end. The arms 16 are carried by a sleeve 20 which sleeve has a crank 21 secured to its end. A connecting-rod 22 connects this crank with a crank 23 on an adjacent shaft so that when 65 this latter shaft is rotated the sleeve 20 car-

rying the feeder will be oscillated. As the feeder is oscillated the projections 18 engage the frame of the lowermost stencil-card in the magazine and move that stencil-card edgewise forwardly into the guides 10, 70 carrying the card along in the guides until its rear edge passes beyond the ends of the levers 12 on the plates 11. The backward movement of the feeder then commences but the stencil-card is held in the position to 75 which it was moved by the spring-actuated brakes or holders 13. As the feeder moves back, the projections 18 catch upon the edge of the rear portion of the frame of the stencil-card, thus moving the card backwardly in the guides 10 until its rear edge 80 engages the ends of the spring-actuated stops or positioning devices 12. These stops arrest further backward movement of the stencil card so that the projections 18 85 yield and pass under the frame of the card, leaving the latter held in the guides 10 by the retainers 13 and positioned against the ends of the levers 12.

The machine shown in the drawings is 90 adapted to be driven by an electric motor 24, connected by a belt 25 with a pulley 26 loose on a shaft 27 mounted in suitable bearings below the top of the table. Secured to the pulley is a pinion 28 which meshes 95 with a gear 29 on a shaft 30 parallel to the shaft 27. The gear 29 meshes with a pinion 31 which in turn meshes with a pinion 32, these two pinions being mounted on shafts 33 and 34 respectively extending across the 100 machine above the table 1. The shaft 34 is carried by arms 35 loosely mounted upon the shaft 34, each of the arms 35 having a rearward extension through which passes a bolt 36 having a threaded end entering an 105 opening in the top of the table. A spring 37 is coiled about the shank of the screw 36 between the table 1 and the arm 35 so that these springs tend to turn the arms 35 about the shaft 33 in a direction to carry the 110 shaft 34 downwardly toward the top of the table. Such downward movement can be regulated by a winged nut 38 on each of the bolts 36. The shaft 34 carries the upper 115 sheet-feeding roller 39. This roller is normally positioned with its lower surface slightly above the upper surface of the table 1 and the width of the space between that surface of the roller and table 1 may be regulated in accordance with the thickness 120 of the sheets or envelopes being fed into the machine. Such sheets or envelopes are fed from the surface of the table 1 and under roller 39, being guided in such movement by fingers 40 which are pivotally mounted 125 upon guides 41, which guides 41 are preferably sheet-metal strips.

The feed of the sheets is effected by the roller 39 and a lower feeding-roller 42 mounted below the roller 39 and movable to- 130

ward and away from the roller 39. The roller 42 is carried by arms 43 which are pivotally mounted on a shaft 44 carried by arms 45 which are rigidly secured to a shaft 46. At its ends the shaft 46 has an arm 47 secured thereto (Figs. 1 and 2), which arm is connected by a link 48 with an arm 49 which is loosely mounted upon the shaft of the gear 29. The shaft of the lower feeding roller 42 is extended to the right, as shown in Fig. 2 and effects the pivotal connection between the link 48 and arm 49. A pinion 50 is mounted upon this shaft 51 and meshes with the gear 29. It will thus be seen that when the motor 24 is in operation the gear 29 will be continuously rotated and will cause rotation of the upper sheet-feeding roller 39 through the pinions 31 and 32. At the same time the lower sheet-feeding roller 42 will be rotated continuously and at the same speed by means of the pinion 50 meshing with the gear 29, but the lower roller 42 can be moved upwardly and downwardly over a short range at any time without disconnecting it from its drive-gear 29 by reason of the fact that the pinion 50 is guided by a link 49 pivotally mounted on the shaft of the gear 29. It is necessary to provide means additional to the gear 29 to guide the shaft of the lower sheet-feeding roller 42 in its upward and downward movement, and in the present instance this is done by the provision of a stationary cam 52 (Fig. 3) which coacts with the shaft 51 or a collar thereon and whose operative surface is shaped to correspond with the curvature of the periphery of the gear 29.

I will now describe the means whereby the vertical movement of the lower sheet-feeding roller 42 is effected at the proper times and whereby suitable adjustment of the time of the movement may be made.

On the shaft 46 is secured an arm 53 and a coiled spring 54 (Fig. 1) connects the free end of this arm with a stud on the bottom of the table 1. The shaft 46 also has an arm 55 secured thereto carrying a roller 56 at its free end, which roller coacts with a cam mounted on a shaft 57. This cam is formed in two parts as shown in Figs. 2 and 12, one part 58 being secured to the shaft 57 and the other part 59 being loose on the shaft. The part 59 has gear-teeth 60 formed thereon at the side of the cam surface. The two parts 58 and 59 of the cam are movable relatively so that the recessed portion of the cam surface may be adjusted in circumferential length in a manner well understood. By this means whenever the depressed portion of the cam surface moves under roller 56, spring 54 rocks rod 46, thereby moving the lower sheet-feeding roller about the axis of gear 29 so that said roller is carried upwardly into coaction with the upper sheet-feeding roller; and when the raised portion

of the cam moves under roller 56, the lower sheet-feeding roller is depressed to its inoperative position.

The shaft 57 is not continuously rotated but its rotation is governed by a clutch operated by a suitable pedal. On the shaft carrying the gear 29 is secured a gear 61 meshing with a gear 62 (Figs. 2 and 12) carried by a sleeve which is loose on the shaft 57. This sleeve has a plurality of pins 63 at its end. Adjacent to the sleeve 64 is a gear 65 secured to the shaft 57 and having an opening therein in which a spring-actuated clutch-block 66 is adapted to reciprocate in the direction of the axis of shaft 57. The clutch is controlled by a pivot-arm 67 (Fig. 7) actuated by a pedal 68. This arm 67 has a beveled end 67' which may be caused to engage the movable clutch-block 66 and carry that block out of coaction with the pin 63. Whenever the pedal is depressed the arm 67 is raised and the clutch-block 66 is moved forward so that any one of the pins 63 on the continuously moving sleeve 64 will engage it and thus cause the gear 65 and shaft 57 to turn with the continuously driven sleeve 64. Such rotation of shaft 57 will continue until the pedal 68 is released, whereupon the arm 67 will disconnect the clutch and bring shaft 57 to rest. When the pedal is released, a spring 68' (Fig. 1) returns it and arm 67 to their former positions and the beveled end 67' of arm 67 is engaged by block 66 which, in riding up the incline on the end of arm 67, is withdrawn from engagement with pin 63 and it and shaft 57 are brought to rest. The cam-section 59 rotates with the shaft 57 at all times in the normal operation of the machine, but while the shaft is at rest an adjustment may be made whereby this cam-section may be moved relatively to the cam-section 58. This adjustment is effected by the parts shown in Figs. 7 and 11. The gear 65 fast on the shaft 57 meshes with a gear 69 loosely mounted upon a parallel shaft 70 and this shaft carries a second loose gear 71 which meshes with the gear 60. The gear 71 has an arc-shaped slot therein as shown in Fig. 7, through which extends a pin 72, the end of this pin being secured to the gear 69. By tightening the wing-nut on the screw 72, the gears 69 and 71 and a coacting plate 73 may be secured together so that all will turn together, and by loosening the nut on the pin 72 the gears 69 and 71 may be moved relatively and when they are so moved the gear 60 will be turned upon the shaft 57 so as to effect the desired adjustment of the cam 59 relative to the cam 58. The adjustment of the gears 69 and 71 may be effected in any desired manner, as for instance by applying force to the nut on the screw 72 move the latter about the axis of the shaft 70 or by direct application of

force to the gear 69. A portion of the gear 71 may have scale markings thereon with which an index on the plate 73 co-acts so that by reference to these scale markings the 5 exact adjustment desired may be obtained.

It will be seen that by adjusting the relative positions of cams 58 and 59 the dwell of the lower sheet-feeding roller in the raised position may be varied as desired. It 10 is only while the lower roll is in this raised position that a sheet is being fed so that in this way the length of the period of sheet feeding may be regulated. This in turn regulates the distance which the sheet will 15 be fed and hence the position at which the address will be impressed upon the sheet. When a sheet is fed between the two sheet-feeding rollers, it is directed downward by the guides 41 and its edge passes between 20 the guides 41 and retaining fingers 74, preferably made of sheet-metal and mounted upon a suitable support below the top of the table, as shown in Fig. 8. If desired, a screw 75 may be provided for adjusting the 25 pressure of the ends of these retaining fingers against the guides 41. By reason of the provision of these guides, when the feeding movement of a sheet is discontinued by the lowering of the lower sheet-feeding roller 30 the sheet will be held in the position to which it has been moved by the fingers 74.

Stop-fingers 76 are provided for assisting in positioning a sheet in the proper initial position. These stop-fingers have upwardly 35 turned projections at their inner ends which extend above the surface of the top of the table just sufficient to catch the edge of a sheet as the latter is moved into the feeding position, but when the lower sheet-feeding 40 roller 42 is raised it engages the edge of the sheet and elevates that edge into coaction with the roller 39 and above the ends of the stop fingers 76, so that these fingers will no longer arrest movement of the sheet.

45 The impression-member consists of a segmental roller 77; that is, a roller having its surface cut away over a portion thereof. This roller 77 is mounted upon the shaft 57. Coacting with it is an ink-pad 78 which is 50 carried by a block 79 mounted upon a shaft 80. This shaft is driven by a gear 81 thereon meshing with the gear 65 on the shaft 57. The inking pad 78 receives ink from a pad 82 carried by a shaft 83 which is driven 55 from the shaft 80 by the gearing shown at the top of Fig. 2. The pad 82 is adapted to coact with an inking-roller 84, the lower surface of which dips into ink in an ink fountain 85 mounted upon the frame of the 60 machine. The gearing for driving the shaft 83 from the shaft 80 is also arranged to drive the shaft 86 on which the crank 23 is mounted.

After the printing has been effected, the 65 wrappers or envelops are moved down-

wardly into a suitable receiving-tray by two rollers 87 and 88. The roller 87 is mounted upon the shaft 27 so that it is continuously rotated when the machine is in operation. The roller 88 is carried by arms 89 which 70 are pivotally mounted upon a stationary shaft 90. One of these arms has an upward extension 91 (Figs. 2 and 3) which carries a roller at its free end adapted to bear upon the periphery of a cam 92 carried by the 75 shaft 99. This cam is adjustable so that the time of movement of roller 88 may be regulated as desired. The cam is so positioned that it will cause the roller 88 to move toward the roller 87 just after the printing 80 has been effected and the sheet has been moved slightly forward by the impression-roller and the inking-pad. An adjustment device (Fig. 8) is provided for keeping the rollers 87, 88 parallel. When the roller 88 85 moves thus, it engages the printed sheet or envelop between it and the roller 87 and as the roller 87 is continuously rotated the two rollers forward the sheet or envelop into a 90 suitable tray.

The stencil-cards move down in the guides 10 after they have been used for printing and fall to the forward end of a receptacle 93. This receptacle has two wheels 94 mounted at opposite sides thereof and provided with (preferably) five blades which enter the sides of the receptacle. One of the wheels 94 has a gear 95 secured to its shaft and meshing with a gear on a shaft 96 rotated intermittently from the shaft 86 by 100 gearing, preferably of the type shown in Fig. 6 and known as a right angle Geneva gear. The shaft 96 also carries a sprocket-wheel 97, having a chain 98 whereby the two wheels 94 are rotated at the same speed. 105 After each stencil-card drops down through the guides 10 into the receptacle 93, the gearing operates to rotate the wheels 94 one step, this one step being equivalent to the angular displacement of two adjacent blades 110 on the wheels 94. In this way each stencil received in the tray is moved up into the body of the tray and all of the stencils accumulated in the tray are moved forward a distance equivalent to the width of one 115 stencil and held in position by the spring guide.

The operation of the machine will be readily understood from the foregoing description. A pile of stencil-cards is placed 120 in the magazine and these are fed one by one from the bottom of the pile and into the printing position where they are held by the retainers 13 and positioned by the stops 12. A plurality of sheets, envelops or cards 125 are laid upon the top of the table 1 in front of the sheet-feeding rollers and these are moved forward by hand one after another between the sheet-feeding rollers where they are arrested by the stops 76 and the guide 130

40. Thereafter the lower sheet-feeding roller is elevated so that the two rollers forward the sheet between them and under the guides 41 until the lower roller is again 5 depressed, whereupon the sheet will come to rest in the position to which it was moved, held by the fingers 74, but while this is being done or after it has been done the operator presses the pedal 68, thereby permitting 10 one revolution of the shaft 57 and the parts actuated therefrom. This causes the impression roller and inking pad to make one revolution and the pad supplies ink to the stencil and through the interstices thereof 15 upon the sheet, thus effecting the printing. Thereafter the sheet is grasped by the forwarding-rollers 87 and 88 and forwarded into a suitable tray and the stencil moves out into the receiver 93 where it is packed 20 in the manner heretofore described. It will be seen that by reason of the peculiar construction and operation of the stencil-feeding devices the stencils will always be in a definite position at the time when the printing 25 is effected, as each stencil will have its rear edge brought up against the ends of the stops 12, one close to each side edge of the stencil. Furthermore the position of the address upon the sheet or envelop may 30 be regulated as desired by regulating the period during which the lower sheet-feeding roller remains in the elevated position. This is in turn regulated by the length of the depressed portion of the composite cam 35 58 and 59. This length may be readily regulated by the gears 69 and 71. During all of the time that the lower sheet-feeding roller is in the raised position, it moves the sheet forwardly, so that the position 40 in which the sheet comes to rest will be determined by the length of the period during which the lower roller remains in raised position.

Having thus described the invention what 45 I claim is:

1. In an addressing machine, an upright magazine for stencils, a pivotally mounted supporting member below the magazine adapted to be reciprocated about its pivot, 50 a picker pivotally mounted on said member and spring-actuated to move its free end toward the stencils in the magazine, and curved guides extending laterally from the magazine and then downwardly, means for holding a stencil in the downwardly extending portions of the guides and co-operating impression and inking members for printing from the stencil when it is held by said means.
2. In an addressing machine, a magazine 55 for stencils, a guide for the stencils leading from the magazine and having a portion thereof directed downwardly, a reciprocating feeding device for feeding stencils from the magazine successively into the guide, a

stop-member past which the stencils are moved adapted to coact with the rear edges of the stencils to position the stencils, and a retainer for holding the stencils in coaction with the stop-member in said downwardly directed portion of the guide. 70

3. In an addressing machine, an upright magazine for stencils, a carrier pivotally mounted below the magazine, a picker pivotally mounted on the carrier and spring-actuated to move its free end toward the stencils in the magazine, means for oscillating the carrier about its pivot, guides extending from the magazine and having a portion thereof directed downwardly, a stop-member adjacent to the guides past which a stencil is moved by the picker and adapted to coact with the rear edge of the stencil to position the latter, and a retainer for holding the stencil in coaction with the stop-member in said downwardly directed portion of the guides. 80

4. In an addressing machine, a magazine for stencil-cards each having a frame, guides leading from the magazine, a reciprocating feeding device having a projection adapted to engage the edge of the frame of a stencil and move the stencil out of and away from the magazine and backwardly toward the magazine, a stop-member mounted adjacent to the guide, means for reciprocating the feeder to cause the projection thereon to engage a stencil and move the latter past the stop-member and then back into coaction with the stop-member and a retaining means 90 for holding the stencil so moved in coaction with the stop-member. 95

5. In an addressing machine, an upright magazine for stencils, a carrier pivotally mounted below the magazine, a picker pivotally mounted on the carrier and spring-actuated to move its free end toward the stencil in the magazine, a projection on the picker adapted to coact with the frame of a stencil to move the stencil out of and away from the magazine and backwardly toward the magazine, a stop-member adjacent to the magazine, means for reciprocating the carrier to cause the projection on the picker to engage the frame of a stencil and move the 105 stencil past the stop-member and then back into coaction with the stop-member, and a retainer for holding the stencil so moved in coaction with the stop-member. 110

6. In an addressing machine, a magazine 120 for stencils, a guide leading therefrom, a plate adjustably mounted upon the guide, two spring-actuated levers mounted on the plate, one displaced from the other in the direction of the length of the guide, and 125 means for feeding stencils successively out of and away from the magazine and beyond one only of said levers and then moving each stencil backwardly into engagement with said lever. 130

7. In an addressing machine, a magazine for stencils, a reciprocating feeding device for feeding stencils therefrom successively, guides through which the stencils are moved by the feeder, a spring-actuated lever for holding the stencils after they are released by the feeder, a platen, an inking device, and means for operating the platen and inking device to cause them to grasp a stencil, withdraw it from the retaining means and move it between the platen and inking means.

8. In an addressing machine, a magazine for stencils, a reciprocating feeder for feeding stencils therefrom successively, a stop member, means for operating the feeder to feed a stencil past the stop-member and then back into coaction with the stop-member, a retainer for retaining the stencil in coaction with the stop-member, a platen, inking means, and means for operating the platen and inking means to cause them to engage a stencil, withdraw it from the retainer and feed it between the platen and inking means.

9. In an addressing machine, a magazine for stencils, a feeder for feeding stencils successively from the magazine and into printing position, sheet-feeding devices, means for operating said devices to feed a sheet between them to printing position and then release the sheet, means for effecting an adjustment of the sheet-feeding devices to vary the distance through which a sheet will be fed thereby, means for sustaining the sheet when it is released by the sheet-feeding devices, a platen, inking means, and means for operating the platen and inking means to grip the stencil in printing position and the sheet held by said sustaining means, print from the stencil upon the sheet and forward the stencil and sheet between them, substantially as set forth.

10. In an addressing machine, an upright magazine for stencils, a pivotally mounted supporting member below the magazine adapted to be reciprocated about its pivot, a picker pivotally mounted on said member and spring-actuated to move its free end toward the stencils in the magazine, guides extending laterally from the magazine and downwardly, a spring-actuated lever into engagement with which the stencils are moved by the picker and which is adapted to hold the stencils in the downwardly extending portion of the guides, and coöperating impression and inking members for grasping a stencil held by said lever, printing from the same and forwarding the stencil between them, substantially as set forth.

11. In an addressing machine, an upright magazine for stencils, guides extending laterally from the magazine and downwardly, stopping and retaining means adjacent to the downwardly extending portion of said guides, means for feeding stencils successively from the magazine through the guides

and beyond the stopping means and then backwardly into coaction with the stopping means to be held there by the retaining means, and coöperating impression and inking members for grasping the stencil held by the retaining means, printing from the same and forwarding the stencil between them, substantially as set forth.

12. In an addressing machine, a magazine for stencils, a guide leading therefrom, stopping and retaining means adjacent to the guide, means for feeding stencils successively from the magazine through the guide and beyond said stopping means and then backwardly into coaction with the stopping means to be there held by the retaining means, and coöperating impression and inking members for grasping a stencil held by the retaining means, printing from the same and forwarding the stencil between them, substantially as set forth.

13. In an addressing machine, a magazine for stencils, a guide leading therefrom, a stop device adjacent to the guide, a feeder, means for operating the feeder to feed stencils from the magazine successively through the guide and beyond the stop device and then backwardly into engagement with the stop device, and coöperating impression and inking members for grasping a stencil in coaction with the stop device, printing from the same and forwarding the stencil between them, substantially as set forth.

14. In an addressing machine, a magazine for stencils, a guide leading therefrom, two spring-actuated levers directed toward the guide, a feeder, means for actuating the feeder to feed stencils successively from the magazine through the guide and beyond one of said levers and then backwardly into coaction with that lever, the other of said levers being adapted to hold a stencil so fed in coaction with the first-named lever, and coöperating impression and inking members for grasping a stencil so held, printing from the same and forwarding the stencil between them, substantially as set forth.

15. In an addressing machine, a magazine for stencils, a guide leading therefrom, a supporting member, a stopping means and a retaining means mounted upon the supporting member, means for securing the supporting member in various positions of adjustment lengthwise of the guide, a feeder, means for operating the feeder to move stencils successively from the magazine through the guide and beyond the stopping means and then backwardly into coaction with the stopping means to be there held by the retaining means, and coöperating inking and impression members for grasping a stencil when in coaction with the stopping means, printing from the same and forwarding the stencil between them, substantially as set forth.

16. In an addressing machine, a magazine for stencils, a guide leading therefrom, a stop device adjacent to the guide, means for moving the stencils successively from the magazine through the guide and beyond the stop device and then backwardly into engagement with the stop device, sheet-feeding devices for feeding sheets successively to a position adjacent to a stencil in coaction with the stop device, and coöperating inking and impression members adapted to grasp a stencil in coaction with the stop device and a sheet adjacent thereto, print from the stencil upon the sheet and forward the sheet and the stencil between them, substantially as set forth.

17. In an addressing machine, a magazine for stencils, a guide leading therefrom, a stop device adjacent to the guide, a feeder for feeding stencils successively from the magazine through the guide and beyond the stop device and then backwardly into coaction with the stop device, sheet-feeding devices, means for operating the same intermittently to feed sheets successively to a position adjacent to a stencil in coaction with the stop device, and coöperating inking and impression members for grasping a stencil in coaction with the stop device and a sheet adjacent thereto, printing from the stencil upon the sheet and forwarding the sheet and stencil between them, substantially as set forth.

18. In an addressing machine, a magazine for stencils, a guide leading therefrom, a stop device adjacent to the guide, a feeder for feeding stencils successively from the magazine through the guide and beyond the stop device and then backwardly into coaction with the stop device, sheet-feeding

devices, means for operating the same intermittently to feed sheets successively to a position adjacent to a stencil in coaction with the stop device, a retaining means for holding a sheet in position when the feeding movement thereof is discontinued, and coöperating inking and impression members for grasping a stencil in coaction with the stop device and a sheet adjacent thereto, printing from the stencil upon the sheet and forwarding the sheet and stencil between them, substantially as set forth.

19. In an addressing machine, a magazine for stencils, a guide leading therefrom, a stop device adjacent to the guide, a feeder for feeding stencils successively from the magazine through the guide and beyond the stop device and then backwardly into coaction with the stop device, sheet-feeding devices, means for operating the same intermittently to feed sheets successively to a position adjacent to a stencil in coaction with the stop device, adjustable devices for varying the extent of the intermittent operation of the sheet-feeding devices to vary the position of a sheet fed thereby with respect to a stencil in coaction with the stop device, and coöperating inking and impression members for grasping a stencil in coaction with the stop device and a sheet adjacent thereto, printing from the stencil upon the sheet and forwarding the sheet and stencil between them, substantially as set forth.

This specification signed and witnessed this 24th day of October, 1912.

WILLIAM W. TUCK.
